UNITED STATES PATENT OFFICE.

LILLIAN GRACE HAKES, OF DANSVILLE, NEW YORK.

HOOK AND EYE.

1,199,067.

Specification of Letters Patent. Patented Sept. 26, 1916.

Application filed May 2, 1914. Serial No. 835,940.

To all whom it may concern:

Be it known that I, LILLIAN GRACE HAKES, a citizen of the United States, residing at Dansville, in the county of Livingston and State of New York, have invented certain new and useful Improvements in Hooks and Eyes, of which the following is a specification.

The object of my invention is to provide a hook adapted to be used in connection with an eye, comprising a body portion and a hook portion bent to be entirely within the body portion and to lie in the same plane therewith.

A further object is to so construct the eye and the hook portion of the hook member, that as the hook is engaged with the eye the structure of the hook portion is sprung to pass through the eye, and when passed through the eye returns to its normal position where it holds the two members against accidental disengagement.

With other objects in view, which will be referred to, my invention consists in the peculiar combination and novel arrangement of parts, such as will be hereinafter more fully described in connection with the accompanying drawing and more particularly pointed out in the appended claim.

In the drawing:—Figure 1 is a view in plan of the hook and eye members connected together to show the relation which they would occupy when in use on the two parts of a garment. Fig. 2 is a view in perspective of the hook member. Fig. 3 is a perspective view to better illustrate the structure of the eye member. Fig. 4 is a fragmentary perspective view to better illustrate the interlocking connection between the two members.

The hook member 1, and the eye member 2, as shown in Fig. 1, are each composed of a single strand of wire bent up to the desired form. The shaping of the hook member 1 might be started at the end 3, from which it is carried forward and the wire is bent around upon itself to form the thread loop 4 and is again carried forward, the strand being then brought back to extend approximately parallel with the portion from the end 3 and bent back again to form the bill or hook portion 5. The bending is continued to form the thread loops 6, side member 7, thread loop 8, thread loop 9 and the end 10 is then carried forward and lapped over the end 3 to complete the structure of the mem-

ber 1. The bill 5 of the hook is shaped on its sides to form the spring shoulders 11 and at its extreme end or nose is bent upwardly slightly, as better shown in Fig. 2, 60 at 12.

The eye member 2 has the thread loop 13 formed at one end, the strand of wire is then carried forwardly and bent back upon itself as at 14 and at the free end a thread 65 loop 15 similar to the loop 13 is provided. The bight 14 of the eye member is bowed at its side at 16 and 17 to form a space of greater transverse dimension than that provided immediately within the bight of this 70 member.

In use, the hook member 1 and the eye member 2 will be attached to the two parts of the garment to be connected together, in the usual manner by sewing through the 75 thread loops of these members. To connect the one member within the other, the eye-member is brought to a position with the bight 14 thereof over the turned-up end 12 of the bill of the hook member, then by exerting pressure laterally of the two members, the spring shoulders 11 on the hook portion 5 of the member 1 are sprung in sufficiently that they pass between the sides 16 and 17 of the member 2 and the bight 14 of the 85 member 2 is brought to a position to bear within the loops 18 between the body portion and the hook portion of the member 1, this relation being better illustrated in Figs. 1 and 4. 90

In the showing in Fig. 2, the hook member 1 is made in a slightly different manner, in this disclosure, the strand of wire from which the member is formed is at the commencement of the bending operation a complete ring, thus when the hook member is completed the side members 7' of the body portion are identical and the ends 3 and 10 which were left in the form hereinbefore described are done away with. 95

From the foregoing, it will be seen that I have provided hook and eye members, which when attached to the garment present a flat structure easily ironed over, and the hook member of which is so constructed that 105 when engaged with the eye it acts to prevent accidental disengagement.

While I have herein shown and described only specific forms of my invention, it will be understood that slight changes might be 110 made in the form and arrangement of the parts as described without departing from

the spirit and scope of my invention, and hence I do not wish to be limited thereto except for such limitations as the claim may import.

5 I claim:—

As an article of manufacture, a hook member to be used in conjunction with an eye member which hook member is bent and shaped from a single piece of wire, the wire being shaped at one end to provide a pair of thread loops arranged in spaced apart relation with a cross bar maintaining this spaced positioning and the extreme end shaped to form a side portion for the hook member, 10 the main extent of the wire wrapped angularly with respect to the cross portion to form the remaining side member of the hook structure, bent and looped to form a

thread receiving eye, shaped to form the bill of a hook, bent and looped to form a thread receiving eye adjacent to the bill of the hook and substantially opposite to the last mentioned eye, and the free end of the wire then bent to act in conjunction with the remaining end to form the completed side of 20 the hook member, the parts being arranged in such a manner that the thread receiving loops and the hook are disposed in the same plane.

25 In testimony whereof I affix my signature 30 in presence of two witnesses.

LILLIAN GRACE HAKES.
